M. A. Page,
Washing Machine.

No. 92540.

Patented July 13, 1869.

Fig. 2.

United States Patent Office.

MOSES A. PAGE, OF LA CROSSE, WISCONSIN.

Letters Patent No. 92,540, dated July 13, 1869.

IMPROVED WASHING-MACHINE.

The Schedule referred to in these Letters Patent and making part of the same.

To all whom it may concern:

Be it known that I, MOSES A. PAGE, of La Crosse, in the county of La Crosse, and State of Wisconsin, have invented a new and useful Improvement in Washing-Machines; and I do hereby declare that the following is a full, clear, and exact description thereof, which will enable others skilled in the art to make and use the same, reference being had to the accompanying drawing, forming part of this specification.

This invention relates to improvements in washing-machines; and consists in a vertical oscillating frame, arranged within a tub provided with vertical rollers around the interior wall, against which the clothes are rubbed by the oscillating frame.

The latter is operated by hand, through the medium of a lever and suitable gearing.

Figure 1 represents a sectional elevation, and

Figure 2, a horizontal section of my improved machine.

Similar letters of reference indicate corresponding parts.

A represents a circular tub, provided with a series of vertical rollers, B, supported in bearings, preferably of brass or other metal that will not corrode, within the wall of the said tub.

C represents a frame, suspended on a vertical shaft, D, consisting of four or any other preferred number of radial arms, from which are suspended the vertical beaters H.

The said shaft is provided at the top with a gear-wheel, E, by which motion is communicated to the frame C, in both directions, from the driving-wheel F and hand-lever G.

The frame C, being moved alternately in both directions, will rub the clothes on both sides; and the whole constitutes a machine capable of washing with great rapidity, and without damage to the clothes.

Having thus described my invention,

I claim as new, and desire to secure by Letters Patent—

The combination of the tub A, with its revolving upright rollers B, arranged around the interior circumference, with the frame C carrying the pendent beaters H, arranged to operate with relation to the rollers B, as herein shown and described.

MOSES A. PAGE.
